[57] CLAIM

The ornamental design for a telephone mouthpiece cover, as shown and described.

DESCRIPTION

FIG. 1 is a top perspective view of the telephone mouthpiece cover of my new design in assembled condition;

FIG. 2 is a side elevational view thereof;

FIGS. 3, 4, 5 and 6 are respectively top perspective, side elevational, top plan, and bottom perspective views of a first portion of the mouth piece cover, the other portions being omitted for purposes of disclosure;

FIGS. 7, 8, and 9 are respectively top plan, side elevational, and enlarged top plan (the bottom being identical) views of a second portion of the mouth piece cover, the other portions being omitted for purposes of disclosure;

FIGS. 10, 11, 12, and 13 are respectively top perspective, side elevational, top plan, and bottom perspective views of a third portion of the mouth piece cover, the other portions being omitted for purposes of disclosure;

FIGS. 14, 15, 16, and 17 are respectively top perspective, enlarged side elevational, enlarged top plan, and bottom perspective views of a fourth portion of the mouth piece cover, the other portions being omitted for purposes of disclosure; and,

FIG. 18 is an exploded view of the telephone mouthpiece cover of my design.
